E. J. SCHELLENTRAGER AND ONE-THIRD TO J. HOMER SCHELLENTRAGER, BOTH OF
PITTSBURGH, PENNSYLVANIA.

RAIL-CLAMP.

1,310,851.

Specification of Letters Patent. Patented July 22, 1919.

Application filed April 24, 1919. Serial No. 292,414.

To all whom it may concern:

Be it known that I, CARLTON A. WILMORE, a resident of Ben Avon, in the county of Allegheny and State of Pennsylvania, 5 have invented a new and useful Improvement in Rail-Clamps, of which the following is a specification.

This invention relates to clamps for securing railroad rails to metallic cross ties, 10 girders or other rigid base or supporting members.

The object of the invention is to provide a clamp which will adjust itself to variations, inequalities and irregularities in either 15 the rail base flange or the supporting cross tie or other member to which the rail is to be secured.

In the accompanying drawing Figure 1 is a transverse section through a rail and the 20 clamp engaging the same; and Fig. 2 is a plan view of the clamp.

In the drawing 1 indicates a railroad rail of standard design having the usual base flanges 2. 3 indicates the base member to 25 which the rail is secured, and which may be a metallic cross tie, a girder or stringer of any kind, or a concrete base or foundation member. 4 indicates the rail clamp, the same having a body of the necessary 30 dimensions and provided at one side with a projecting lip 5 which extends over the rail base flange and has its lower face shaped to conform to the upper face of the rail base flange. The body of the clamp is provided with a hole 6 for receiving the fastening bolt 10, which will extend through or be anchored in the foundation or base supporting member 3. This hole 6 is slightly elongated in a direction normal to the axis 35 of the rail, as shown in Fig. 2, thereby allowing for the adjustment of the clamp toward and from the rail in order to accommodate itself to variations in thickness or width of the rail base flange, or in the 40 position of the rail relative to an anchored 45

fixed bolt, and nevertheless permit the clamping lip 5 to properly seat on the rail base flange. This hole is furthermore flared, that is, increased in size from the central portion of the body both upwardly and downwardly, in order that the clamp may adjust 50 itself by tilting either lengthwise around the end angle 9, or sidewise, to accommodate itself to irregularities in either the rail base flange, or in the cross tie or other foundation member. This hole is flared in a manner to bring the wall portion 7 thereof parallel to the wall portion 7^a and the wall portion 8 parallel to the wall portion 8^a, as a result of which the clamp can tilt slightly 55 in any direction, even though the bolt fill the hole fairly well.

This clamp will be made in several standard sizes to accommodate rails of various weights. It will preferably be made by a 60 forging operation, in suitable dies shaped to give the final form to the clamp, the dies being provided with projecting portions to form the hole 6.

I claim:

1. A rail clamp having a body provided 70 with a lip to extend over the rail base flange and provided with a bolt hole which increases in size from approximately the vertical middle of the body toward both the 75 top and bottom faces thereof.

2. A rail clamp having a body provided with a lip to extend over the rail base flange and provided with a bolt hole which is elongated in a direction normal to the rail 80 to be clamped and increases in size from approximately the vertical middle portion of the body toward both the top and bottom faces thereof.

In testimony whereof I have hereunto set 85 my hand.

CARLTON A. WILMORE.
